UNITED STATES PATENT OFFICE.

JAMES TOMLINSON, OF DETROIT, MICHIGAN, ASSIGNOR OF ONE-HALF TO
GEORGE MAITLAND, RALZEMOND A. PARKER, AND CHARLES F. BURTON,
ALL OF SAME PLACE.

CYLINDRICAL WOODEN PACKAGE.

SPECIFICATION forming part of Letters Patent No. 336,963, dated March 2, 1886.

Application filed November 25, 1884. Serial No. 148,833. (No model.)

To all whom it may concern:

Be it known that I, JAMES TOMLINSON, of Detroit, in the county of Wayne and State of Michigan, have invented a new and useful 5 Improvement in Cylindrical Wooden Packages; and I do hereby declare that the following is a full, clear, and exact description thereof, reference being had to the accompanying drawings, which form a part of this specification.

10 The invention relates to wooden packages; and it consists of a cylindrical-shaped package, the walls of which are formed of two thicknesses of wood wound in a continuous coil from one piece, and having interposed between them a cement saturated piece of cloth or paper. The inner and outer coils are composed of one piece, and they inclose the cement-coated paper or cloth between them.

15 Figure 1 is a perspective view of the wall or cylinder of such package. Fig. 2 shows a sectional view of the cylinder, showing especially the manner of fastening and cementing the heads into said package. Fig. 3 is a plan 20 view of the top of the cylinder. Fig. 4 is a view of the top of the cylinder. Fig. 4 is a detail showing the strip of wood with the strip of paper or cloth before it is rolled into cylindrical shape.

25 The cylinder is made of two or more layers 30 of wood wound in a continuous coil from a single piece, the strip of wood being cut of sufficient length to make the desired number of coils.

35 As shown in Fig. 4, A represents the wooden strip with the strip of cloth B, saturated with glue or other similar cement, or a strip of paper covered on both sides with cement, applied to one side of the wood. The wood strip is then coiled into proper shape in the 40 ordinary manner, a full turn causing the uncovered portion of the strip A to lap under the portion covered by the cloth or paper strip B. The coiling of the strip A is continued until a second turn has been completed, 45 when the end of the strip of wood is secured to the body of the cylinder and prevented from uncoiling by riveting, nailing, or sewing, the strip of cloth or paper B being thus interposed between the coils of the wood strip, as 50 shown in Fig. 3.

Instead of forming the package as above described, I may form it in the following manner: After the full turn of the coil has been made and the wood begins to lap upon itself I insert the strip of cloth or paper, saturated 55 or coated as described. The coil of wood and the strip of cloth or paper is continued until a second turn has been completed, when the end of the strip is secured to the body, as before described.

60 I secure the head D in position in the following way: A suitable head-lining, c, is secured near the end with cement or glue, and the head forced into place. This construction may be adopted for both headings, but I have 65 shown the bottom K held in differently, the inside coil of the package being cut away to allow of the bottom being forced into place, where it is held by cement or nails. The top head I may slightly bevel, so that when placed 70 upon the head-lining there is an annular V-shaped groove, c', between the walls of the package and the head.

75 Before using the package I saturate its inside with a bath of hot paraffine or paraffine and resin, which enters the pores of the wood and renders it impervious to aqueous mixtures. The top also has its lower or inner surface coated with the paraffine.

80 After filling the package with whatever it may be desired to keep therein, I place the top in position, and fill the V-shaped groove with the paraffine cement, which at the same time secures the head in place and closes any 85 aperture between the walls of the package and the head, securely confining the contents of the package.

86 What I claim as my invention is—

90 A cylindrical-shaped package the walls of which are formed of two thicknesses of wood wound in a continuous coil from one piece, and having interposed between them a cement-saturated piece of cloth or paper.

JAMES TOMLINSON.
